BOILER

Henry Dieterlen, Paris, France

Application January 21, 1931, Serial No. 510,300,
and in France January 21, 1930

4 Claims. (Cl. 122—367)

The present invention relates to heat exchangers such as boilers or economizers, having sets or groups of tubes provided with fins, and has for one of its main objects to provide improved means whereby a better exhaustion may be obtained along the length of the tubes thus materially simplifying the construction of such devices.

According to the present invention, I provide 10 a heat exchanger having tubes arranged between headers at each end provided with longitudinal fins the depth of which alters from one end to the other.

The fins may increase uniformly in depth 15 from one end to the other. The axes of the tubes may be parallel, or they may be inclined at an angle to one another so that the adjacent edges of the fins are more or less parallel.

The invention is represented diagrammatically 20 in the accompanying drawing, in which:

Figure 1 shows adjacent elements of a group of boiler tubes provided with fins according to the invention;

Figure 2 is a modification of the arrangement 25 shown in Figure 1, and

Figure 3 is a view partly in elevation and partly in section of a nest or group of tubes constructed according to the invention and adapted to be used, for example, as a boiler economizer.

30 In Figure 1, the tubes 7 provided with the fins 8 increasing in depth, are mounted in parallel relation, whereas in Figure 2 the tubes 7 are disposed at an angle with respect to one another so that the adjacent edges of the fins 7 are relatively parallel.

In Figure 3 the groups of boiler tubes of the type mentioned is shown. This group has a header 10 at the top of the tubes 7 and a header 11 at the lower part of these tubes for each set 40 of tubes 7 having fins 8.

The headers 10 and 11 are disposed outside of the direct current of gas, which passes through the flue 9 as indicated by the arrows. The fins 8 terminate at a certain distance from each 45 header in order to facilitate the circulation of the gases around the ends of the tubes adjacent to the headers, and about the whole nest of tubes.

As represented in Figure 3, soot blowers 14 50 may be provided, and also sight holes 15. The soot blowers are preferably arranged with their axes parallel to the longitudinal fins of the tubes so that the flanges or fins 8 thereof serve as guides for the cleaning fluid while the latter is 55 projected about said tubes by said soot blowers.

From the foregoing, it will be understood that the tubes being arranged between headers with in a flue and the fins terminating at such distance of said headers, the gaseous current is admitted freely throughout the whole nest of tubes.

The tubes may be arranged in rows, adjacent tubes in each row being parallel.

By increasing the depth of the flanges or fins 8 in the direction of the gas flow along the tubes, a uniform absorption of heat is obtained along 65 the length of the tubes.

Having now particularly described and ascertained the nature of my invention and in what manner the same is to be performed, I declare that what I claim is:

1. A heat exchanger comprising a plurality of 70 headers, a nest of tubes arranged between and connected to said headers, means causing heating gases to flow generally longitudinally of said tubes, flanges on said tubes and extending longitudinally thereof, the depth of said flanges being increased in the direction of gas flow along the tubes, whereby a good absorption of heat may be obtained along the length of the tubes.

2. A heat exchanger comprising a plurality of 80 headers, a nest of tubes arranged between and connected to said headers, means causing heating gases to flow generally longitudinally of said tubes, flanges on said tubes and extending longitudinally thereof, the depth of said flanges being increased uniformly in the direction of gas flow along the tubes whereby a uniform absorption of heat may be obtained along the length of the tubes.

3. A heat exchanger comprising a plurality of 85 headers, a nest of tubes arranged between and connected to said headers with their axes parallel, means causing heating gases to flow generally longitudinally of said tubes, flanges on said tubes and extending longitudinally thereof, the depth of said flanges being increased uniformly in the direction of gas flow along the tubes whereby a uniform absorption of heat may be obtained along the length of the tubes.

4. A boiler comprising a plurality of headers, a 90 nest of tubes arranged between and connected to said headers, means causing heating gases to flow generally longitudinally of said tubes, flanges on said tubes and extending longitudinally thereof, the depth of said flanges being increased in the direction of gas flow along the tubes, fluid 95 soot cleaning means adapted to project the cleaning fluid in planes substantially parallel to the axis of said tubes and said flanges serving as guides for the cleaning fluid while the latter is 100 projected about said tubes.

HENRY DIETERLEN.
